Gerrit Van Daam,
Attorney.

By

UNITED STATES PATENT OFFICE.

GERRIT VAN DAAM, OF BUFFALO, NEW YORK.

CONVERTIBLE COAL SAVER AND GAS BURNER.

Application filed January 20, 1921. Serial No. 438,798.

To all whom it may concern:

Be it known that I, GERRIT VAN DAAM, a citizen of the United States, residing at Buffalo, in the county of Erie, State of New York, have invented a new and useful Convertible Coal Saver and Gas Burner, of which the following is a specification.

My invention relates to convertible coal, or other fuel saver and gas burner for furnaces or stoves. The object is to provide a device adapted to deliver heated air to the combustion chamber of a furnace or stove, which by providing a suitable delivery end, and providing a gas supply nozzle at the intake end the device is also adapted to deliver and burn gas mixed with heated air in said combustion chamber.

Referring to the drawings which illustrate, merely by way of example, suitable means for effecting my invention—

Fig. 1 is a side elevation in part section showing my device adapted to deliver heated air to the combustion chamber.

Fig. 2 is a plan view of the outlet end of the same.

Fig. 3 is an end elevation showing the air inlet regulator valve.

Fig. 4 is a side elevation of my device converted to deliver and burn gas in the combustion chamber.

Fig. 5 is a plan view of the gas burner end of the same.

Similar numerals refer to similar parts throughout the several views.

The pipe 8 is exteriorly threaded throughout the greater part of its longitudinal extension. It is adapted to be inserted in a suitable hole provided in the door frame or other part of a furnace or stove, and is held in place by the nuts 7 threaded upon said pipe 8. The outer end of this pipe 8 is flaring or funnel shaped, as at 9, and is provided with a valve or regulator plate 10 held in place by screw 10', which permits a certain rotative movement of said valve plate to regulate the amount of air that may pass into said pipe 8. Upon the inner end of pipe 8 is adjustably secured the end member 11, in Fig. 1, having an interior thread to cooperate with the exterior thread of pipe 8. This end member is provided with a bulb formation 12 having a substantially spherical chamber 13, and upon one or more parts of its periphery there is provided a substantially square

lug or block 14, through which are provided the cross cuts 15 forming a corresponding shaped vent from said chamber 13. Within this cross-shaped vent 15 is preferably inserted the wire gauze or screen 16.

Within the main extension of pipe 8 is removably inserted the spiral formation 17.

In operation the air in the chamber 13 becomes heated from the fire in the combustion chamber, and passes out through the vent or vents 15 and, mingling with the gases resulting from the combustion of the fuel, greatly facilitates the combustion of these gases in a way well understood in the art. As the heated air passes out of chamber 13 through vent 15, fresh air is drawn in through pipe 8. The spiral formation 17 tends to retard the passage of air through pipe 8 to chamber 13, so that the air becomes more thoroughly heated in said passage. Another function of the spiral formation, is that, in retarding the passage of air through pipe 8, it serves to make the flow more regular and less susceptible to fluctuations in the draft connected with the furnace. In fact the flow of air into and from chamber 13 is largely due to the heating of the air in the bulb and to this extent is independent of the draft connected with the furnace, and stove.

Where it is desired to convert the device into a gas delivery and burning device, the spiral formation 17 is preferably removed. The end member 11 is also removed and the burner member 18 is threaded on to pipe 8 as shown in Fig. 4. This burner member 18 is so formed that its discharge end has its axis at right angles to the axis of its main extension. This discharge end is flaring or bell-shaped. Over this flaring discharge end is adjustably secured the plate 19 by means of the threaded stud 20 secured in the lug 21 in the body of member 18 near its bend. Between the flaring end and the plate 19 is formed the annular slit or burner-vent 22, which may be made larger or smaller as desired, by turning the plate 19 on its threaded supporting stud 20.

At the flaring intake end 9, is provided a centrally disposed threaded hole 23 in which is secured a suitable end or nozzle 24 of a gas supply pipe 25, controlled by the valve 26.

In this combination the plate or valve 10

is adjusted to admit the necessary supply of air to insure proper mixing with the gas and proper combustion at the annular burner vent 22. The long pipe extension 5 between the intake end 9 and the burner vent 22 secures a thorough mixing of the gas and air and a perfect distribution at the annular vent 22. The burner end may be arranged to discharge upwardly, or may 10 be inverted to discharge downwardly, in which latter case, that is, in the inverted position, the burning gas thoroughly heats the burner and the gas therein, thus preventing any moisture from escaping into 15 the combustion chamber of the furnace or stove.

What I claim is:—

1. In a fuel saving device, the combination of an air conductor, leading from the 20 exterior to the interior of a combustion

chamber, a chambered body disengageably secured to the inner end of said conductor and provided with a comparatively restricted discharge vent, and means for disengageably associating a fluid fuel supply 25 with the air intake of the conductor.

2. In a fuel saving device, the combination of a air conductor, leading from the exterior to the interior of a combustion chamber, a chambered body disengageably 30 secured to the inner end of said conductor and provided with a comparatively restricted discharge vent, and means for disengageably associating a fluid fuel supply with the air intake of the conductor, so that 35 the device is adapted to deliver to the combustion chamber, either heated air, or a mixture of heated air and fluid fuel, as required.

GERRIT VAN DAAM.
